I. W. NONNEMAN,
PIPE WRENCH,
APPLICATION FILED APR. 30, 1919.

1,340,622.

Patented May 18, 1920.

UNITED STATES PATENT OFFICE.

IRA W. NONNEMAN, OF WARREN, OHIO, ASSIGNOR TO THE BORDEN COMPANY, OF WARREN, OHIO, A CORPORATION OF OHIO.

PIPE-WRENCH.

1,340,622.

Specification of Letters Patent. Patented May 18, 1920.

Application filed April 30, 1919. Serial No. 293,634.

To all whom it may concern:

Be it known that I, IRA W. NONNEMAN, a citizen of the United States, residing at Warren, in the county of Trumbull and 5 State of Ohio, have invented a certain new and useful Improvement in Pipe-Wrenches, of which the following is a full, clear, and exact description, reference being had to the accompanying drawings.

10 The object of this invention is to provide a pipe wrench which, while being efficient, shall be extremely simple and may be very cheaply constructed. The invention consists of the combinations of parts having the 15 characteristics hereinafter explained which enable this combined efficiency, simplicity and cheapness.

In the drawings, which illustrate my invention, Figure 1 is a side elevation of the 20 wrench; Fig. 2 is a plan or edge view of the same; Fig. 3 is a cross section, as indicated by the line 3-3 on Fig. 1; Fig. 4 is a cross section at right angles to Fig. 3 of the yoke detached; Fig. 5 is a fragmentary side elevation of a portion of the handle member of the wrench.

As shown in the drawings, my wrench comprises four members, namely: the two 30 jaw members 1 and 10, the yoke 20 connecting them, and the nut 30 connecting the member 10 with the yoke.

The member 1 may be a single integral bar extended to form a handle 2 which is preferably recessed at its opposite sides at 35 3 for lightness. On the inner end of this bar is a head 4 laterally enlarged, carrying teeth 5 at its edge, and having a pair of downwardly extending wings 6 spaced apart. On the opposite sides of the bar are recesses 7 40 formed in the upper portion just back of the head 4. Intermediately in these recesses are outwardly projecting bosses 8.

The other wrench member 10 has a rectangular shank 11 provided with external 45 threads 12 and 13 on the top and bottom respectively. At its far end this member is turned up in an elbow form 14 provided with teeth 15.

The yoke member 20 which connects the 50 two jaw members described is a box-like structure having two parallel side plates 21 and cross connections 22 at the top and 23 at the bottom. The distance between the two inner faces of the side walls of this 55 yoke is only slightly greater than the width

of the jaw members 1 and 10. On each inner face of the yoke near the upper end is a pair of cheeks 24 which leave between them a recess 25, semi-circular at the top. When the yoke is in place these cheeks occupy the recesses 7 of the bar 1, while the space 25 is occupied by the cylindrical bosses 8 on the bar.

Clearance is provided as shown in Fig. 1 between the members 1 and 10 and between 65 the lower edges of the cheeks of the yoke and the base of the recesses 7, and the under face allows the member 1 to rock in the yoke with the bosses 8 as a pivot. On the forward edge of the yoke near its lower portion the walls 21 have projections indicated at 28 to coact with the edges of the wings 6 of the member 1 and limit the rocking.

By obtaining the rocking connection between the handle member and the yoke by 75 means of the integral bosses on the handle member occupying the recesses in the yoke, I do away with the necessity of a separate pivot pin. I thus save the expense of drilling openings for such a pin and also reduce 80 the labor in assembling the tool.

The nut 30 is simply a ring having an internal thread adapted to engage the threads 12 and 13 formed on the upper and lower edges of the shank 11. Externally the nut 85 is preferably knurled or roughened. The nut surrounds the shank and occupies openings 29 in the side walls of the yoke. Clearance is provided for it on the under side of the bar 1, which preferably depends at 90 9 in front of it.

In assembling the device the yoke is passed over the handle 2 and placed in position adjacent to the head 4 with the cheeks engaging the upper half of the bosses 8. The nut 95 is placed in the openings 29 and then the shank 11 is put into the yoke and the nut rotated to screw the shank into place, as shown in Fig. 1.

In the operation of the wrench, the nut is 100 turned to adjust the jaw space to that required to engage the pipe or other article to be turned. Then, when the pressure is applied to the handle 2 (in the upward direction in Fig. 1) the two jaws relatively 105 rock to allow the biting engagement of such pipe. The setting of the jaws is preferably such that the wings 6 do not engage the edge of the yoke, and thus the pull on the handle is resisted only by the pipe, as will 110

be well understood. The wings 6 form desirable lateral guides for the shank of the member 10.

In the economical manufacture of the 5 wrench the two jaw members may be drop forged, the yoke member may readily be a malleable casting and the nut is a simple screw machine product. The only machine work needed is on the nut and the teeth of 10 the jaws. The parts may thus be cheaply made and they are very readily assembled.

Having thus described my invention, what I claim is:

1. In a pipe wrench, the combination of 15 two members, each having a jaw and a shank, one of said shanks being externally threaded, a yoke embracing the shanks, a nut on the threaded shank rotatively connected with the yoke, recesses formed in the 20 opposite sides of the shank of the other member, and projections on the inner faces of the yoke occupying said recesses.

2. In a pipe wrench, the combination of a 25 member having a jaw and a shank with bosses formed on the opposite sides of the shank adjacent to one longitudinal edge thereof, a second member having a jaw and a shank adapted to lie adjacent to the other longitudinal edge of the shank first mentioned, 30 a yoke embracing the two shanks and having cheeks formed on its inner faces where it embraces the shank first mentioned, said cheeks providing recesses occupied by the bosses, and a nut adjustably connecting 35 said yoke with the second shank.

3. In a pipe wrench, the combination of a 40 member having a jaw and a shank with integral bosses formed on the opposite sides of the shank adjacent to one longitudinal edge thereof, a second member having a jaw and a shank adapted to lie adjacent to the other longitudinal edge of the shank first mentioned, a yoke embracing the two shanks and having cheeks formed on its inner faces 45 where it embraces the shank first mentioned, said cheeks providing recesses occupied by the bosses, said yoke having openings through its side walls transversely alining with the recesses between the cheeks and on 50 directly opposite sides of the second shank, and a nut embracing said second shank and occupying said openings.

4. In a pipe wrench, the combination of a member having a jaw and a shank, recesses

in opposite sides of the shank, integral cylindrical bosses within said recesses, a yoke embracing the shank and having on each of its inner faces a pair of cheeks separated by a recess semi-circular at the top, said last named recesses receiving said bosses as pivots 60 for the yoke, the second member having a jaw and a shank, and a nut connecting said second member with said yoke.

5. In a pipe wrench, the combination of a member having a jaw and a shank, recesses 65 in opposite sides of the shank, bosses formed on the sides of the shank in said recesses, a yoke embracing the shank and having cheeks on its inner faces, occupying said recesses, and openings on each side between the cheeks 70 occupied by the bosses, a second member having a jaw and a shank, and a nut adjustably connecting said second member with the yoke.

6. In a pipe wrench, the combination of a 75 member having a jaw and a shank, recesses in opposite sides of the shank, cylindrical bosses formed on the opposite sides of the shank in said recesses, a yoke embracing the shank and having on each of its inner faces 80 a pair of cheeks separated by a recess semi-circular at the top, said recesses being occupied by said bosses, a second member having a jaw and a shank extending through said yoke, said shank having teeth on its upper and lower edges, and a ring nut embracing such teeth and occupying openings in the two sides of the yoke.

7. In a pipe wrench, the combination of a member having a shank and a head, the 90 head having teeth and a pair of depending wings, another member having a head with teeth and having a shank, said shank lying between the wings of said head, a yoke embracing the two shanks, the shank which lies 95 between the wings being threaded on its upper and under edges, and a nut embracing such threaded portion and extending outwardly through openings in the opposite sides of the yoke, the yoke having on its inner face near its upper end a pair of cheeks separated by a space and the corresponding shank having recesses in its opposite sides occupied by the cheeks and bosses occupied by the space between the cheeks.

In testimony whereof, I hereunto affix my signature.

IRA W. NONNEMAN
